GAS BURNER

**John C. Rogers, Cicero, Ill., assignor to Crown
Stove Works, Cicero, Ill., a corporation of
Illinois**

Application July 2, 1934, Serial No. 733,439

3 Claims. (Cl. 158—116)

The present invention relates to burners for gas stoves, ranges, and the like, having reference more particularly to burners of the annular type.

5   Burners of this type are commonly formed with variously grouped jet ducts in the top wall thereof, one known arrangement consisting of concentric inner and outer rows of ducts bordering the inner and outer peripheral walls of the
10 burner.

10 The burner of my present invention is based on the last-mentioned type, but, with a view to greater efficiency and reduced cost of manufacture, substitutes for the outer row of jet ducts 15 a continuous horizontal annular duct or aperture communicating with the chamber of the burner ring and opening through the ring between the top and outer peripheral walls thereof, so as to provide a continuous annular sheet 20 flame surrounding and concentric with the inner row of jet flames. It also includes other structural features hereinafter described and claimed.

A preferred embodiment of the invention is disclosed in the accompanying drawing, in which—

Fig. 1 is a top plan view with the mixer tube broken out.

Fig. 2 is a central vertical section on the line 2-2 of Fig. 1.

30 Fig. 3 is a side elevation.

As stated above, one purpose or object in the development of the present improvement has been to reduce the cost of manufacture, and this is accomplished mainly through a one-piece construction of burner which may also include the usual mixing tube as an integral part thereof. The hollow burner ring is made as a cored casting, and comprises an outer peripheral wall 10, an inner peripheral wall 11, a bottom wall 12, and a top or cover wall 13. As clearly shown in Fig. 2, the top wall 13 is made integral or continuous with the top edge of the wall 11, and substantially at the juncture of said walls 11 and 13 there is drilled a circular row of jets 14, which preferably are slightly inclined upwardly toward the axis of the burner ring. The outer edge of the top wall 13 is spaced from the top edge of the outer peripheral wall 10 to form a continuous narrow horizontal annular aperture 15 communicating with the chamber of the burner ring and, when the burner is ignited, giving a continuous annular sheet flame at the outer edge of the burner.

16 designates the mixing tube which, in the present instance, is conveniently and economi-

cally cast integral with the burner ring itself, as shown in Fig. 2. This mixing tube is provided at its outer end with the usual gas cock and air-regulating valve (not shown).

The efficiency of burners of this type depends, to a large extent, on the provision of an adequate supply of secondary air to the flame jets. This secondary air is not admitted through the burner and jet ducts, but is an external upward flow of air around the burner induced by the heated condition of the air directly above the burner; and the more perfectly such draft of secondary air is brought into contact with the Bunsen flame, the purer and hotter the flame will be. With a view, therefore, to providing for the ample flow of secondary air to the outer annular sheet flame issuing from the aperture 15, I give the outer surface of the wall 10 an upward flare, and form thereon a ring of flutes 17, the upper ends of which merge into the aperture 15 at an acute angle to the plane of the latter. I also preferably form on the inner peripheral wall 11 similar flutes 18 disposed between adjacent jet ducts 14, whereby an ample volume of secondary air is supplied to the jet 25 flames issuing from the ducts 14.

The efficiency of a Bunsen burner also depends, to some extent, on the thoroughness and uniformity with which the gas and primary air admitted through the mixing tube are commingled before the mixture is ignited. With a view to improving the present burner in this regard, I form on the internal walls of the burner ring flutes or corrugations 19 and 20 which act as baffles on the inflowing gas and primary air and effect a thorough mixture of the two before they reach the burner passages 14 and 15.

At opposite points on the burner ring are offsets 21 formed with apertures 22 that communicate with the chamber of the ring, and at an intermediate point is an offset 21' formed with an aperture 22' that communicates with the mixing tube 16. These provisions are for use in connection with channels or conduits for lighting the burner. 45

Specific details of the structure herein shown and described may be varied within the principle of the invention and without sacrifice of its efficiency for the purposes stated; and hence, I do not limit the invention to the specific structure presented for purposes of illustration, but reserve such modifications and variations as fall within the spirit of the appended claims. The term "ring" as used herein is not intended to be limited to a circular structure, since obviously 55

the burner may be round, oblong, or polygonal within purview of the invention.

I claim—

- 5 1. A gas burner, comprising a one-piece hollow ring formed in its top wall with a row of upwardly and inwardly inclined jet ducts bordering its inner periphery and communicating with the chamber of said ring, the inner peripheral wall of said ring being formed with flutes between adjacent ducts of the row for the passage of secondary air; said ring also having a continuous horizontal annular flame aperture opening above its outer peripheral wall just below the outer periphery of said top wall and said top wall being formed as an integral extension of said inner peripheral wall.
- 10 2. A gas burner, comprising a one-piece hollow ring having a continuous horizontal annular aperture between its top and outer peripheral walls, said outer peripheral wall formed on its outer side with a row of upwardly and outwardly inclined flutes meeting said aperture at an acute
- 15
- 20

angle to the plane of the latter for the flow of secondary air.

3. A gas burner, comprising a one-piece hollow ring formed in its top wall with a row of upwardly and inwardly inclined jet ducts bordering its inner periphery and communicating with the chamber of said ring, the inner peripheral wall of said ring being formed with flutes between adjacent ducts of the row for the passage of secondary air; the top wall of said ring being formed as an integral extension of said inner peripheral wall and its outer peripheral portion overlying and narrowly spaced from the top edge of the outer peripheral wall to form a continuous horizontal annular flame aperture, and said outer peripheral wall being formed on its outer side with a row of upwardly and outwardly inclined flutes meeting said aperture at an acute angle to the plane of the latter for the flow of secondary air.

JOHN C. ROGERS.
